JOHN W. GARVER AND CHARLES A. BIKLE, OF HAGERSTOWN,
MARYLAND.

Letters Patent No. 86,746, dated February 9, 1869.

IMPROVEMENT IN THRESHING-MACHINES.

The Schedule referred to in these Letters Patent and making part of the same.

To all whom it may concern:

Be it known that we, JOHN W. GARVER and CHARLES A. BIKLE, of Hagerstown, in the county of Washington, and State of Maryland, have invented a new and useful Improvement in Threshing-Machines; and we do hereby declare that the following is a full and exact description thereof, reference being had to the accompanying drawings, and to the letters of reference marked thereon.

Our invention consists in a novel construction and arrangement of threshing-machines.

In the accompanying drawings—

Figure 1 is a vertical longitudinal section of our threshing-machine.

Figure 2 is a detached view of the metallic plate holding the cylinder.

In the construction of our threshing-machine, the main frame and threshing-cylinder may be of the usual construction.

We also employ a celled and ribbed apron, A, to carry the straw, grain, and chaff to the separator.

This apron A is made wider than the length of the threshing-cylinder, so as to project on both sides; and the metallic head-piece B is made with a curve outward, as seen at b, fig. 2, in order to prevent the grain and chaff from leaking over the edges of the apron, and also to give a wider separating surface.

A series of separating-rakes, D, are arranged upon two cranks, E, having four bearings each. These bearings are placed at right angles in the same crank, and the two cranks set at corresponding angles, so as to make both ends of a rake-head or bar rise and fall at the same time.

Between the rakes are intermediate bars G, with holes g, to allow the grain to fall through.

At each end of the fan we employ a peculiar form of register, O, shown in fig. 1, the openings into the fan and the form of the register being such as to close or open rapidly the air-spaces near the circumference of the fan, while the air-spaces near the centre of the fan are slowly opened and closed.

By this arrangement, when a small amount of air is admitted to the fan, a greater proportion of the air enters near the centre, and thus is able to reach the middle of the machine, and prevent an excess of blast at the ends of the fans, and a weak blast near the middle of the machine.

For the purpose of operating this register by the blast itself, and for keeping a balance between the

speed of the fan and the amount of air admitted, we have pivoted a board, H, in the fan-case, in such manner that a strong blast will swing the board back from the fan, and thus, by means of a link, I, connecting the board to the register, the latter is closed. When the speed diminishes, this board, by its own weight, swings down, and immediately opens the register. Thus strength of the blast is kept uniformly the same, whether the speed of the machine is greater or less.

By means of a ribbed roller, K, chaff and other impurities are carried over, and thus separated from the grain.

Near this roller is placed a concave board, which receives grain and impurities, and holds the same in the blast until the good grain backs off against the blast which carries the light grain and impurities out of the machine.

The metallic comb L rests upon a shelf, M, and is made adjustable, in order to separate different kinds of grain.

Having thus fully described our invention,

What we claim, and desire to secure by Letters Patent of the United States, is—

1. The metallic head-pieces B, with the extensions b, for preventing the grain and chaff from leaking over the edges of the apron, and also to give a wider separating space, substantially as set forth.

2. The apron A and intermediate bars G, with holes, in combination with the rakes working upon two cranks, with bearings at different angles, to avoid dead-centres, substantially as set forth.

3. A register, so arranged and operated as to cut off the admission of air near the circumference of the fan, and admit the full or near the full amount of air at the centre of the fan, substantially as specified.

4. Carrying chaff and other impurities over or away, by means of a ribbed roller, K, substantially as specified.

5. The concave board P, for receiving grain and impurities, and holding the same in the blast until the good grain backs off, while the impurities are carried along with the blast, substantially as set forth.

6. The metallic comb L, used in the manner and for the purposes specified.

JOHN W. GARVER.
CHARLES A. BIKLE.
